JONATHAN B. GERMAN, OF WALNUT HILLS, OHIO.

Letters Patent No. 63,239, dated March 26, 1867.

IMPROVED CAR-COUPLING.

The Schedule referred to in these Letters Patent and making part of the same.

TO WHOM IT MAY CONCERN:

Be it known that I, JONATHAN B. GERMAN, of Walnut Hills, Hamilton county, Ohio, have invented a new and useful Car-Coupling; and I hereby declare the following to be a full, clear, and exact description thereof, reference being had to the accompanying drawings, making part of this specification.

My invention relates to that class of mechanism by which railway cars are connected together, and consists in a device by which the coupling or connecting is rendered entirely automatic, and the uncoupling or disconnecting, under certain circumstances, automatic also, so that while a train of cars is moving properly along the track, the coupling mechanism remains, as usual, intact, yet subject to instant release by the proper officials; but should a portion of the train be thrown by accident sufficiently off the rails to endanger the safety of the train, the instant that a car to which my invention is attached becomes diverted beyond a certain angle from the true line of the track, the automatic mechanism operates, and the divergent car becomes detached from the train, thus preventing the remainder from being dragged over the side of an embankment or bridge by the weight of the engine, tender, or car first deflected. The automatic coupling is further calculated to do away with a class of accidents resulting from brakemen being frequently jammed between the buffers of cars while endeavoring to insert the coupling-pin.

Figure 1 is a horizontal section of a coupling embodying my invention, in its normal condition.

Figure 2 is a similar section through the couplings of two cars, deflected at such an angle as to show the manner of automatic release in case of accident.

A is the body of the coupling "draw-head," of cast iron or other suitable material, having the usual cheeks *a a'* for the insertion of the connecting-link B, which, instead of having the usual shape of an elongated ring, is a bar having a hook at each end, *b b'*, turned in opposite directions, and a shoulder, *c c'*, on each side a short distance from the centre of the bar. In coupling cars, the bar entering the jaws of the coupling-head presses aside a curved spring, D, until it has entered a sufficient distance for the hook *b* to engage around the coupling-pin E, where the spring tends to hold it in position as long as the cars remain in the same line, or nearly so, but should they be deflected to an abrupt angle, as in fig. 2, the shoulder *c* pressing against the cheek *a*, the bar B at once acting as a lever throws back the spring D and detaches the cars, the bar becoming released at one end or the other as they turn to the right or left. A lever, F, pivoted at *f*, inside the draw-head, affords the means of voluntarily detaching the cars by pressing the hook *b* off of the coupling-pin, throwing back the spring D and releasing the bar B. This lever may be operated by the conductor or other proper official by a cord, or any other simple mechanical device. A spring, G, causes the automatic retraction of the lever F. The coupling-pin E may be capable of withdrawal or insertion in the customary way.

I claim herein as new, and of my invention—

1. The self-releasing car-coupling, composed of the draw-head A, reversely hooked bar B, formed with shoulders *c c'*, the spring D, and coupling-pin E, combined and adapted to operate in the manner set forth.
2. The combination of the lever F, hooked bar B, spring D, and coupling-pin E, constructed and arranged to operate substantially as set forth.
3. The connecting-bar B, having reversely-directed hooks *b b'*, and shoulders *c c'*, and capable of instant release when in direct line either by withdrawal of the coupling-pin E or by advance of the lever F, or, when out of direct line, by the automatic action of the parts, in the manner set forth.

In testimony of which invention I hereunto set my hand,

J. B. GERMAN,

Witnesses:

GEO. H. KNIGHT,
JAMES H. LAYMAN.
